[57] CLAIM

The ornamental design for an immunity analyzer, as shown and described.

DESCRIPTION

FIG. 1 is a front, top and left side perspective view of an immunity analyzer showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side view thereof;

FIG. 7 is a left side view thereof;

FIG. 8 is a front, top and left side perspective view of the immunity analyzer during operation;

FIG. 9 is a front elevational view thereof during operation;

FIG. 10 is a rear elevational view thereof during operation;

FIG. 11 is a top plan view thereof during operation;

FIG. 12 is a bottom plan view thereof during operation;

FIG. 13 is a right side view thereof during operation; and,

FIG. 14 is a left side view thereof during operation.

The broken line showing in the FIGS. 8 through 14 are for illustrative purposes and forms no part of the claimed design.
